[57] CLAIM

The ornamental design for a humorous novelty item, as shown and described.

DESCRIPTION

FIG. 1 is an environmental perspective view of a humorous novelty item with the case in a closed position showing my new design;

FIG. 2 is a top view of my new design with the case in an open position;

FIG. 3 is a front elevational view thereof;

FIG. 4 is a rear elevational view thereof;

FIG. 5 is a left side elevational view thereof; and,

FIG. 6 is a right side elevational view thereof.

The undisclosed bottom view of the case is plain and unornamented. The broken line showing of the indicia in FIG. 1 is for illustrative purposes only and forms no part of the claimed design.
